LOOM HARNESS

John Jacob Kaufmann, Elkins Park, Pa., assignor
to Steel Heddle Manufacturing Company,
Philadelphia, Pa., a corporation of Pennsylvania

Application September 27, 1947, Serial No. 776,431

6 Claims. (Cl. 139—92)

1

This invention relates to loom harness, and it relates more particularly to that type of harness which, while of general application, is particularly useful in installations where the warp ends are inserted through the heddles by means of the automatic warp drawing-in machines which are now more or less in common use.

More specifically considered, this invention relates to the construction and arrangement of loom harness of the general type shown and described in my previous Letters Patent No. 2,386,690, but in which a duplex arrangement is provided whereby two sets of heddles are mounted in the same frame on separate pairs of supporting rods.

When it was attempted to apply the principle shown in my previous Letters Patent No. 2,386,690 to the duplex arrangement, certain difficulties arose which, however, have been overcome by the arrangement shown and described herein.

The principal object of the present invention is to provide a heddle frame of the character aforesaid, in which two sets of heddles are mounted on separate pairs of supporting rods, either pair of which may be detached from the frame without disturbing the other, or, either pair of which may be shifted longitudinally to an intermediate position for the purpose of removing heddles therefrom or for adding heddles thereto, as is required in changing over for the weaving of fabrics of different count.

The nature and characteristic features of the present invention will be more readily understood from the following description, taken in connection with the accompanying drawings forming part hereof, in which:

Figure 1 is a front elevation of a loom harness frame embodying the main features of the present invention, the same being shown with heddles mounted therein which are particularly adapted for use in installations in which warp drawing machines are used for the purpose of entering the warp;

Fig. 2 is an enlarged fragmentary view of a portion of the heddle frame, certain parts being shown in section for the purpose of more clearly illustrating the construction and arrangement of the means for supporting the heddle rods intermediate their ends;

Fig. 3 is a vertical section taken approximately on the line 3—3 of Fig. 2; and

Fig. 4 is a horizontal section taken approximately on the line 4—4 of Fig. 2.

It should of course be understood that the description and drawings herein are illustrative

2

merely, and that various modifications and changes may be made in the structure disclosed without departing from the spirit of the invention.

Referring to the drawings, the heddle frame proper may be of any preferred construction. For example, as shown, the same may comprise the usual top and bottom rails 10 connected at their ends by end struts 11. The heddle supporting rods 12 are made of strips of flat bar metal and extend from end to end of the frame. Each rod 12 has its end portions mounted in slots in the end struts 11 of the frame in the usual and customary manner. Each of the projecting end portions of each heddle rod 12 may also be provided with the usual aperture 15, engaged by the hooked end of a spring retaining member 16 mounted in the end strut 11 of the frame.

It should of course be understood that other forms of mounting and securing the ends of the heddle rods 12 may be used if desired.

The heddle rods 12 are provided, at each of the places where a supporting device is located, with a plate member 17 which is secured to the heddle rod by means of rivets 18; and a spacing member 19 is interposed between the heddle rod 12 and the plate member 17 in a manner similar to that shown in my previous Letters Patent hereinbefore referred to.

It should be noted, however, that at each location the plate member 17 which is secured to one of the upper heddle bars is spaced longitudinally from the plate member 17 which is secured to the other of the upper bars, and the same arrangement is also used in connection with the lower heddle bars.

Each of the plate members 17 extends toward the frame rail 10 from which the heddle rod 12 is supported, and each of said plate members is provided near the edge thereof with a longitudinal slot 20. The slot 20 of each plate member 17 is engaged by a horizontal lug 21 provided by bending over the end portion of a vertical extension 23 of a bracket 24.

Each plate member 17 is also provided with a tongue portion 25 which extends from one of the end margins of plate member 17 and is bent around and engages one face of the vertical extension 23 of the bracket 24. It should be noted however that the tongue portion 25 of the plate member 17 which supports one of the heddle rods from a particular bracket is in each instance connected to the said plate member at the end thereof most remote from the other adjacent plate member.

It should also be noted that the tongue portions 25 of the plate members 17 supported by a particular bracket are disposed in the same plane. The foregoing arrangement is provided so that the respective heddle rods may be freed from their supporting bracket by sliding the same longitudinally, but in opposite directions.

It should also be noted that the bent around tongue portion 25 of the plate member 17 in each instance terminates at such point as to permit the bent around lug portion 21 of the vertical extension 23 of bracket 24 to be disengaged from the slot 20 of the plate member 17 when the heddle supporting rod has its end portions disengaged from the retaining hooks and is slid endwise a sufficient distance.

The bracket 24 has a body portion 26 extending parallel to the heddle bars 12, which is seated in a recess in the inner edge portion of the rail 10. The horizontal body portion 26 of the bracket member 24 is fixedly secured to the inner end of a bolt member 27 which is provided at its outer end with a threaded portion 28. The threaded portion 28 of the bolt member 27 is engaged by a complementally threaded sleeve 29.

The sleeve 29 is provided with a flange 30 near its outer end and is also provided with a head portion 31, having a transverse slot for adjustment of the bracket member by means of an ordinary screwdriver. The flange 30 of the sleeve 29 is confined between an inner plate member 32 and an outer plate member 33, which are secured in the rail 10 by means of screws 34.

The sleeve 29, mounted on the threaded end of the bolt, permits an adjustment of the bolt 27 in the frame thereby to maintain the heddle supporting rods 12 in the frame at the proper distances apart, and in proper parallelism.

The heddles 35 may be substantially the same as those shown in my previous Letters Patent hereinbefore referred to, being preferably made from thin flat strips of metal of a width corresponding to the widest portion of the heddle. The central portion 36 of each heddle 35 is preferably left the full width of the strip, as is also each end portion 37 thereof, but the parts 38 of each heddle, between the central portion 36 and the respective end portions 37, are preferably cut down to a considerably narrower width to reduce the weight of the installation, and to permit each heddle 35 to be twisted as required for the functioning of the warp drawing-in machine during the entering operation.

The central portion 36 of each heddle 35 is provided with the usual punched and formed warp eye 39, the shanks of which may, if desired, be formed in bowed conformation out of the main plane of the heddle proper.

Each of the end portions 37 of each of the heddles 35 shown is left the full width of the strip from which the heddle is formed, is punched out to provide a slot 41 for mounting the heddles on the rods 12, and one side portion thereof is cut away as at 42, substantially midway the extension of the slot 41, so that when the heddles are slid sidewise on the rods 12, during the entering operation, they will pass freely without being obstructed by the spacing members 19 which are disposed between the heddle rods 12 and the plate members 17 each forming part of the supporting means for the rods intermediate the ends.

It should be noted that the open sides of the end portions 37 of the heddles are disposed inwardly, as is shown in Fig. 3 of the drawings.

By the foregoing arrangement there is provided a duplex harness frame which is particularly adaptable for use in connection with installations in which warp drawing-in machines are used for the purpose of entering the warp.

It will be apparent that whenever it is desired to add heddles on a particular pair of supporting rods it is only necessary to release the proper hock members at the ends and then slide the heddle rods a short distance to free the ends thereof from the struts of the frame.

When, however, it is desired to entirely remove the heddle supporting rods on one face of the frame, the heddle rods will be slid to a greater extent whereby the plate members 17 carried by the particular rods will be brought to such position as to cause the ends of the tongues 25 to clear the coacting portions 23 of the bracket member 24.

It will, of course, be apparent that the heddle supporting rods, on one face of the frame may have heddles added thereto or removed therefrom, or the rods and the heddles thereon may be entirely removed from the frame without disturbing the heddles carried by the heddle supporting rods on the other face of the frame.

I claim:

1. In loom harness including a heddle frame having top and bottom rails and a pair of heddle supporting rods at the top and at the bottom adjacent said rails, said heddle supporting rods comprising thin flat metallic strips removably mounted in said frame, the means for supporting said rods intermediate the ends thereof comprising, at each location, a bracket mounted in the rail, a member secured to each rod, and said members being spaced longitudinally of said rods, said members detachably engaging said bracket, and means for normally maintaining said members in locked engagement with the bracket.

2. In loom harness including a heddle frame having top and bottom rails and a pair of heddle supporting rods at the top and at the bottom adjacent said rails, said heddle supporting rods comprising thin flat metallic strips mounted in said frame and being removable therefrom by sliding lengthwise, the means for supporting said rods intermediate the ends thereof comprising, at each location, a plate member secured to each rod, the plate member secured to one of the rods being spaced longitudinally of said rods with respect to the plate member secured to the other of said rods, a bracket mounted in the rail, said plate members being in locked engagement with the bracket member, and means for normally maintaining the locked engagement of said members.

3. In loom harness including a heddle frame having top and bottom rails and a pair of heddle supporting rods at the top and at the bottom adjacent said rails, said heddle supporting rods comprising thin flat metallic strips mounted in said frame and being removable therefrom by sliding lengthwise, the means for supporting said rods intermediate the ends thereof comprising, at each location, a plate member secured to each rod, the plate member secured to one of the rods being spaced longitudinally of said rods with respect to the plate member secured to the other of said rods, a bracket member mounted in the rail, said plate members being in locked engagement with the bracket member, said plate member being separable from the bracket member upon sliding the rod lengthwise, and tongue mem-

bers for normally maintaining the locked engagement of said members.

4. In loom harness including a heddle frame having top and bottom rails and a pair of heddle supporting rods at the top and at the bottom adjacent said rails, said heddle supporting rods comprising thin flat metallic strips mounted in said frame and being removable therefrom by sliding lengthwise, the means for supporting said rods intermediate the ends thereof comprising, at each location, a plate member secured to each rod, the plate member secured to one of the rods being spaced longitudinally of said rods with respect to the plate member secured to the other of said rods, a bracket member mounted in the rail, one of said members being slotted and the other of said members having a portion engaging the slot to secure said members in locked engagement with each other, said plate member being separable from the bracket member upon sliding the rod lengthwise, and means for normally maintaining the locked engagement of said members.

5. In loom harness including a heddle frame having top and bottom rails and a pair of heddle supporting rods at the top and at the bottom adjacent said rails, said heddle supporting rods comprising thin flat metallic strips mounted in said frame and being removable therefrom by sliding lengthwise, the means for supporting said rods intermediate the ends thereof comprising, at each location, a plate member secured to each rod, the plate member secured to one of the rods being spaced longitudinally of said rods with respect to the plate member secured to the other of said rods, a bracket member mounted in the rail, said plate members each being slotted and the bracket member having portions engaging the slots to secure said members in locked engagement with each other, said plate members being separable from the bracket member upon sliding the rod lengthwise, and tongues for normally maintaining the locked engagement of said members.

ing the slots to secure said members in locked engagement with each other, said plate members being separable from the bracket member upon sliding the rods lengthwise, and means for normally maintaining the locked engagement of said members.

6. In loom harness including a heddle frame having top and bottom rails and a pair of heddle supporting rods at the top and at the bottom adjacent said rails, said heddle supporting rods comprising thin flat metallic strips mounted in said frame and being removable therefrom by sliding lengthwise, the means for supporting said rods intermediate the ends thereof comprising, at each location, a plate member secured to each rod, the plate member secured to one of the rods being spaced longitudinally of said rods with respect to the plate member secured to the other of said rods, a bracket member mounted in the rail, said plate members each being slotted and the bracket member having portions engaging the slots to secure said members in locked engagement with each other, said plate members being separable from the bracket member upon sliding the rod lengthwise, and tongues for normally maintaining the locked engagement of said members.
